Inventor:
Alexander Nullau,
by *Alexander S. Lauer*,
His Attorney,

UNITED STATES PATENT OFFICE.

ALEXANDER NULLAU, OF BERLIN-NIEDERSCHONHAUSEN, GERMANY, ASSIGNOR TO
GENERAL ELECTRIC COMPANY, A CORPORATION OF NEW YORK.

SYSTEM AND APPARATUS FOR SIGNALING.

Application filed March 10, 1923, Serial No. 624,233, and in Germany March 18, 1922.

One of the objects of the invention is to provide an improved system and improved apparatus for signaling in which an electrically controlled machine is controllable from 5 any one of a plurality of similar control stations located at different control points. Another object of the invention is to provide a system and apparatus for signaling, whereby the signal which is given at the 10 controller which has been operated is different from the signal which is given at the other control stations, so that the control station from which the electrical machine or device has been operated is easily recognizable.

For a better understanding of the invention, reference is had to the following specification taken in connection with the accompanying drawing wherein Fig. 1 is a top plan view of a start and stop push button controller with a locking device for the stop push button in locking position, so as to give a different signal at this controller than at the other control stations; Fig. 2 is a 20 cross-section of the controller of Fig. 1 taken on the section lines 2-2; Fig. 3 is a cross-section of the controller indicating the locking device for the stop push button in the released position so as to shield or screen 25 the light emitted from the signal lamp; Fig. 4 is a detail of a push button control system for a printing press or the like in which the separately operable controllers are located at different control stations about the press or 30 other machine to be controlled, and Fig. 5 is a very simple diagram illustrating the interconnections of the stop push button switches and the interconnections of the signal lamps of the various stations.

In electrically controlled machines, it is 35 customary to provide an arrangement whereby the driving machine can be controlled at various points. Such an arrangement is very commonly used in electrically driven 40 printing presses. In order to directly show at the various control stations the operating condition existing with respect to the printing press, corresponding signals are arranged 45 for at the various control stations. Thus, for example, in the case of operation of the printing presses, variously colored lights are 50 lighted, according as to whether from the point of control the motor for threading

the paper or the main driving motor is in circuit, or if the press has been stopped. If 55 the stopping of the press is indicated, for example, by a red lamp, then red lamps will burn at every control station as soon as one of the controllers at a control station has been operated to stop the press. The operators of the machine can therefore see at once and directly that the operation of the 60 press has been stopped, even though the control station at which the stopping of the 65 press has been effected cannot be seen from the other control stations. In order to discover the controlled station at which the stopping of the press has been effected, a 70 more thorough search must be made of the various controlled stations, since the position of the push button usually employed as the controller is only distinctly visible near the control station. In accordance with this 75 invention, this defect is overcome and the control station at which the stopping of the 80 press has been effected is clearly indicated, in that a different signal appears at this control station than at the other control stations. Similar incandescent lamps may be 85 used at all of the control stations, and in order to indicate the particular control station at which the stopping or other operation 90 of the press has been effected, the locking device for locking the push button is made use of. When the locking device is out of 95 cooperative relation with the push button, it will partially shield the light emanating from the lamp at that particular controller, but when the locking device is operated, the light emitted from the lamp at that control 100 station will not be shielded or screened. Thus, the lamp at the controller which has been operated will burn brighter and give a 105 different visible signal than the lamps at the other control stations.

Referring to the drawing, the push button controller or control station is provided with a start and stop push button, and associated with the stop push button is a locking device 10 which cooperates with the stop push button 11 so as to hold the contract disc 12 out of engagement with the stationary contacts 13 and 14. This locking device may be held in the locking relation by inserting 105 a locking member through the hole in the post 15. Associated with each controller is

an incandescent lamp 16, the light from which is arranged to be shielded or screened by the flap 10 when the flap is out of locking engagement with the stop push button, 5 as indicated in Fig. 3. As will be seen from this figure, that the light from the lamp will shine through the slots in the flap 10 so as to give a very much different signal from the signal which is given by the light 10 from the lamp shining freely through the opening in the top of the controller when the locking flap is in locking relation with the stop push button, as indicated in Figs. 1 and 2. Any suitable arrangement may be 15 provided whereby the incandescent lamps at all of the control stations *a*, *b*, *c*, etc., (Fig. 4), may light when the stop push button of any one of the controllers has been operated. The conductors of the control system of the press may be carried in the cable 17, as is customary. In Figs. 2 and 3 I have indicated that the contact disc 12 is arranged to complete a circuit through the down contacts 13^a and 14^a when the disc is held in 20 its lowermost position, and in Fig. 5 I have indicated that with the disc 12 in its lowermost position the circuit for controlling the motor (not shown) which drives the printing press or other device, is opened so as to 25 stop the controlled motor by the contact disc 12 breaking engagement with the contacts 13 and 14 at the station *a*. This figure also indicates that with the contact disc 12 in its lowermost position, the signal lamp 16 at 30 station *a*, the signal lamp 16^a at station *b* and the signal lamp 16^b at station *c* are all connected in multiple relation across the supply circuit indicated by the plus and minus characters so that these signal lamps will 35 all be lit. This figure also indicates that when the stop push button at any one of the stations *a*, *b* or *c* is depressed, the circuit 40 for controlling the motor is opened so as to stop the motor, and the signal lamps at the various stations are all lit by reason of the engagement of the push button contact with these lower station contacts. This arrangement is merely diagrammatic and for 45 the purpose of indicating a suitable arrangement whereby the operation of the stop push button not only effects the stopping of the controlled motor, but also the lighting of the various signal lamps. I have not indicated a complete motor control system in which the stop push button switches are included, since such arrangements are well known and those skilled in the art will readily understand the application of the invention to the 50 common practice in control systems of this sort.

It will be apparent from the above description that the visible signal which is given at the control station at which the operation of the machine driving the printing press has been controlled is very much dif-

ferent from the signal that has been given at all of the other control stations. Thus, in Fig. 4 the controller *a* has been operated and the signal lamp at this station burns freely, whereas the signal lamps at stations *b* and *c* are screened.

In accordance with the provisions of the patent statutes, I have described the principle and operation of my invention, together with the apparatus which I now consider to represent the best embodiment thereof, but I desire to have it understood that the apparatus shown is only illustrative, and that the invention can be carried out by other means.

What I claim as new and desire to secure by Letters Patent of the United States, is,—

1. In a system of signaling for indicating the intended operation of a device, a plurality of separately operable controllers interconnected to control the device from any one of a plurality of different control stations, means for giving a visible signal at all the control stations to indicate the operation of any one of the controllers, and means whereby the signal which is given at the controller which has been operated is different from the signal which is given at the other control stations.

2. In a system of signaling for indicating the intended operation of a device, a plurality of separately operable controllers interconnected to control the device from any one of a plurality of different control stations, a lamp at each control station which is connected to be lit when any one of the controllers has been operated, and means whereby the signal which is given by the lamp at the controller which has been operated is different from the signal which is given by the lamps at the other control stations.

3. In a system of signaling for indicating the intended operation of a device, a plurality of separately operable controllers interconnected to control the device from any one of a plurality of different control stations, a lamp associated with each controller which is connected to be lit when any one of the controllers has been operated, and means for locking the controller which has been operated and for altering the signal which is given by the lamp at the controller which has been operated, whereby the signal given by the lamp at the controller which has been operated is different from the signal given by the lamp at the other controllers.

4. In a system of signaling for indicating the intended operation of a device, a plurality of separately operable controllers interconnected to control the device from any one of a plurality of different control stations, a lamp associated with each controller and connected to be lit when any one of the controllers has been operated, a locking de-

vice for each controller arranged to normally shield a portion of the light emitted from the lamp at the control station when the locking device is out of locking relation with the controller, the said locking device arranged to remove the shield from the lamp at the particular control station when the locking

device is in operative relation, whereby the signal given at the controller which has been operated is different from the signal which is given at the other control stations. 10

In witness whereof, I have hereunto set my hand this twelfth day of February, 1923.

ALEXANDER NULLAU.
